COMBINED TISSUE DISPENSER AND LITTER CONTAINER FOR AUTOMOBILES

Daniel C. Larkin, 3134 Woodstock Drive,
Detroit, Mich. 48221

Filed Mar. 30, 1965, Ser. No. 84,516

Term of patent 14 years

(Cl. D58—12.6)

FIG. 1 is a front perspective view of a combined tissue dispenser and litter container for automobiles, showing my new design with a tissue box being indicated by means of broken lines for illustrative purpose;

FIG. 2 is a rear perspective view with the cover partially open and a tissue box being indicated by means of broken lines for illustrative purpose;

FIG. 3 is a side elevational view; and

FIG. 4 is a front elevational view thereof.

The dominant features of my design reside in the portion shown in full lines.

I claim:

The ornamental design for a combined tissue dispenser and litter container for automobiles, as shown and described.
